UNITED STATES PATENT OFFICE.

WILLIAM HUGHES, OF WAUPUN, WISCONSIN, ASSIGNOR TO HIMSELF AND JOHN FIELDSTAD.

IMPROVED LIFE-BOAT.

Specification forming part of Letters Patent No. **56,855**, dated July 31, 1866.

To all whom it may concern:

Be it known that I, WILLIAM HUGHES, of Waupun, Fond du Lac county, in the State of Wisconsin, have invented a new and Improved Life-Boat; and I do hereby declare that the following is a full and exact description thereof, reference being had to the accompanying drawings, and to the letters of reference marked thereon.

The nature of my invention consists in providing a life or other boat with two chambers on or between its sides, one for water and one for air, the latter above the former, the object being that of safety.

To enable others skilled in the art to make and use my invention, I will proceed to describe its construction and operation, like parts being designated by like letters in the several figures.

In the drawings, Figure 1 represents an elevation of my boat, and Fig. 2 a cross-section on line *a b*.

On each side of the boat, and extending fore and aft of the dividing-line of its length, I construct two chambers or apartments, *A* and *B*, the former below the latter, and separated from each other by a partition, *C*. These chambers may occupy from one-half to three-fifths of the length of the boat. The lower apartment will be more or less filled with water, according to the draft of the boat. There are holes *a* through the bottom of this chamber—

that is, through the bottom of the boat. These are intended to empty the chamber when the boat is taken out of the water, as also to let the water in when the boat does not sit in the water deep enough to let it in through the opening *a'* at the top of the chamber.

The top chamber, *B*, is an air-chamber, so the one acts as a buoy and the other as ballast, and they co-operate to keep the boat from capsizing, and this co-operation takes place, not on the same side of the boat, but on different sides; for in case of tipping, while the water-chamber on one side acts as a ballast to keep down that side, the air-chamber on the other side acts as a buoy to keep its side up, thus preserving, as far as possible, an equilibrium.

Air enters the upper chamber through the opening *a''*.

Having thus described my invention, what I claim as new, and desire to secure by Letters Patent of the United States, is—

A boat having the two chambers *A* and *B* on each side, the former being a water-chamber, open at bottom *a* and at top *a'*, as also the latter being an air-chamber, open at bottom *a''*, the two having a partition, *C*, between them, arranged, constructed, and co-operating in the manner described, and for the purpose set forth.

WILLIAM HUGHES.
